Primary Examiner — Doris Clark(57) **CLAIM**

The ornamental design for a partition apparatus, as shown and described.

DESCRIPTION

FIG. 1 is a front perspective view of a partition apparatus showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom view thereof; and,

FIG. 7 is a right-side elevational view thereof, the left-side elevational view being a mirror image thereof.

The broken lines showing of base assembly in FIGS. 1-7 are included for the purpose of showing environmental structure and form no part of the claimed design.

1 Claim, 7 Drawing Sheets(56)
